4 SHEETS--SHEET 1.

The diagram illustrates the magnetic field and current flow in a three-phase induction motor. It features three circular regions representing the stator and rotor. Magnetic field lines, labeled with numbers 11, 10, 9, and 8, are shown as closed loops. Current directions are indicated by arrows: a clockwise arrow in the top-left circle, a counter-clockwise arrow in the top-right circle, and a clockwise arrow in the bottom circle. The bottom circle is labeled with numbers 12, 13, and 14.

UNITED STATES PATENT OFFICE.

EUGENE FRIEDLAENDER, OF BRADDOCK, PENNSYLVANIA, ASSIGNOR TO WESTINGHOUSE ELECTRIC & MANUFACTURING COMPANY, A CORPORATION OF PENNSYLVANIA.

HOIST OPERATING AND CONTROLLING SYSTEM.

1,175,350.

Specification of Letters Patent. Patented Mar. 14, 1916.

Application filed April 23, 1913. Serial No. 763,072.

To all whom it may concern:

Be it known that I, EUGENE FRIEDLAENDER, a citizen of the United States, and resident of Braddock, in the county of Allegheny and State of Pennsylvania, have invented certain new and useful Improvements in Hoist Operating and Controlling Systems, of which the following is a specification.

10 My invention relates to the construction and arrangement of means for regulating and controlling the operation of electric motors, employed in actuating hoists, elevators, and the like, and, although not restricted to 15 such uses, the invention more particularly relates to the construction and arrangement of means employed in regulating and controlling the operation of motors for skip hoists, forming part of the equipment of 20 mechanically charged blast furnaces, the invention being peculiarly well adapted for use on single skip hoists, which have unbalanced loads.

One object of this invention is to provide 25 a hoist operating and controlling system of improved construction having novel means whereby the hoist is automatically caused to travel through a selected distance and whereby the speed of the hoist is varied in 30 predetermined portions of its travel through such selected distance.

Another object of my invention is to provide 35 a hoist operating and controlling system whereby, after the apparatus is set in motion, the buckets or cars of the skip hoists are automatically caused to move first slowly and at a gradually accelerating speed, then at maximum speed and to then gradually slow down, and are always brought to 40 rest or stopped in the same position at each end of the travel independently of and without reference to fluctuations in the weight of the successive loads on the hoist, to the hoist operator or to the supply of current to 45 the driving motor.

A further object of the invention is to provide 50 a hoist operating and controlling system having novel means whereby the apparatus is rendered inoperable or the direction of travel is reversed or by which the hoist is caused to stop with entire safety at any point in the length of travel.

A still further object of this invention is

to provide a hoist operating and controlling system having improved means whereby the 55 operation of the hoist driving motor is regulated and controlled in case of an overload or when the power is shut off, or in the event of accident to the motor or the mechanism connecting the motor and skip buckets or cars.

Still other objects of my invention will become apparent as the co-acting mechanical and electrical features of the invention are hereinafter more fully described and 65 claimed.

Referring to the accompanying drawings forming part of this specification and showing my improved automatic operating and controlling system as applied for use on the 70 double skip hoist of a mechanically charged blast furnace, Figure 1 is a plan illustrating the manner in which the automatic controller and the safety cut-out are mechanically connected to the skip hoist driving mechanism. Fig. 2 is a side elevation, on an enlarged scale, showing the construction of the automatic controller and the connections thereto forming part of my invention. Fig. 3 is a sectional end elevation of 80 the controller, the section being taken on the line III—III of Fig. 2. Fig. 4 is a sectional side elevation of my improved controller as connected to the skip hoist, the section being taken on the line IV—IV of 85 Fig. 1. Fig. 5 is a sectional end elevation on the line V—V of Fig. 4 showing the construction of the weighted swinging arms and the quick-break switches forming part of the controller mechanism. Fig. 6 is a 90 sectional end elevation of the apparatus shown in Figs. 1 to 5, the section being taken on the line VI—VI of Fig. 4. Fig. 7 is a plan showing, diagrammatically, the wiring system and arrangement of switches and relays forming part of this invention. Fig. 8 is a diagrammatic plan showing one arrangement of gears connecting the drum shaft and the automatic controller in accordance with my invention. Fig. 9 is a similar 95 diagrammatic plan showing one arrangement of gearing for connecting the safety cut-out with the drum shaft in accordance with this invention.

In the accompanying drawings the number 105 2 (see Fig. 1) designates one end of

the rope drum of a motor driven double skip hoist having an automatic, mechanically actuated controller 3, a mechanically operated safety cut-out 4 and a manually controlled operator's switch 5 that are operatively connected in accordance with my invention.

The hoist shown being a double skip hoist, a load will be lifted by a skip car or bucket 10 when the rope drum 2 is rotated in either direction.

The rope winding drum 2, upon which the hoisting ropes are coiled and uncoiled in operating the hoist, has a shaft 6 which is 15 rotatably mounted by its ends in pedestal bearings 7 (of which but one is shown) and the construction of the drum, not forming part of this invention, is not further described.

20 The end of the drum shaft 6 which projects through the bearing 7, has a spur driving pinion 8 keyed or otherwise secured thereon which meshes with and drives an idler spur gear 9 rotatably mounted on a 25 stub shaft 10, which is secured to and projects from the side of the pedestal bearing 7. The spur gear 9 is connected to and drives a spur pinion 11 on the shaft 10 which, with the gears 8 and 9 forms the reduction 30 gear mechanism operatively connecting the spur gear 12 to the drum shaft 6, the gear 12 being mounted to rotate on the controller shaft 13 when the rope drum 2 is moved.

35 The controller shaft 13 is rotatably mounted by one end in a bushed dead-eye bearing 14 which is conveniently formed in the pedestal bearing 7, and is located below and to one side of the axial center of the drum shaft 6.

40 The opposite end of the controller shaft 13, which projects through the bushed opening in the stand 15 forming part of the controller, is provided with a double arm 16, keyed or otherwise secured thereon to rotate 45 or oscillate with the shaft 13. The arm 16 is provided on opposite sides of its pivotal center with a series of electrically connected contact fingers 17, 18, 19 and 20 and 21, 22, 23 and 24 which are positioned at separated 50 intervals in the length thereof and engage with the faces of the series of segmental contacts on the controller in a manner to be described. Also keyed to the shaft 13, at an intermediate point in the length of the shaft 55 is a wheel 25, (see Figs. 4 and 6) having removable lugs 26 and 27 adjustably secured on its periphery. These lugs, which are made adjustable to enable variations being made in the length of travel of the 60 skip cars or buckets, engage with the lug 28 on the side of the spur gear wheel 12, so that the wheel 25 is caused to turn on its axis in either of opposite directions when the gear 12 is actuated through the medium 65 of the gears 9 and 10 and the gear 8 secured

on the end of and rotating with the drum shaft 6. The wheel 25 is also provided with lugs 29 and 30 which extend outwardly on one side near the periphery of the wheel and are arranged to engage with the lugs 31 and 32 located on the side of swinging weighted arms 33 and 34 which are pivotally secured by one end to turn on the shaft 13 between the wheel 25 and the frame or stand 15 of the controller 3. The arms 33, 34 are, by 75 engagement with the respective lugs 31 and 32, caused to lift or swing when the wheel 25 is moving through certain arcs or portions of its rotary or oscillatory paths of movement.

80 Secured to a boss 35 on the inner face of the controller stand 15, is a stop 36 having faces 37 and 38 which are arranged to be engaged by the end faces 39 and 40 of the weights on the swinging outer ends of the 85 arms 33 and 34 and thereby limit the downward swinging movement of these arms in the operation of the controller.

85 Fastened on the upper end of the inner or rope drum side of the controller stand 90 15, is a suitable insulating material 41 and secured in suitable openings or holes in this insulation, so as to project beyond the surface thereof, are pins 42, 43 and 44, 45 (see Fig. 5) which are arranged in pairs and form 95 part of the quick-break switches comprising part of the control circuit operatively connecting the controller 3 with the magnetic switches and relays of the switchboard, these quick-break switches being arranged 100 to break the control circuit in bringing the skip cars or buckets to a stop at the end of the upward and downward travel thereof.

105 The pairs of pins or contacts 42-43 or 44-45 are engaged, when the quick-break switches are closed, by metal disks 46 and 47 which are arranged to bridge the gap between the adjacent pins in each pair, a disk being rotatably secured in the fork of the bifurcated outer or swinging end of 110 each of the levers 48 and 49. Each of the levers or arms 48 and 49 is pivotally secured at one end to the insulating material 41 and is provided at an intermediate point in its length with a projection or lug 50 positioned 115 to be engaged by the bent outer end 51 or 52 of the swinging levers or arms 53 and 54 also pivotally secured at one end to the insulating material 41. Stops 55 are provided on the slab or sheet of insulating material 41 120 to limit the downward swinging movement of the arms 53 and 54. The arms 53 and 54 also have lugs 56 and 57 respectively at intermediate points in their lengths which are adapted to be engaged by the end of cap 125 bolts 58 and 59 respectively. The bolts 58 and 59 are adjustably secured in screw-threaded holes in the lugs 60 and 61 on the side of the weighted swinging end of the weighted lever arms 33 and 34, and lock- 130

nuts 62, 62 on each bolt serve to hold the cap-bolts 58 and 59 in adjusted position on the arms 33 and 34.

As will be seen by reference to Fig. 5, the point of engagement between the cap-screw 58 and lug 56 and the cap-screw 59 and lug 57 on the respective swinging arms 53 and 54 is at a point located between the middle of the length and the pivot end of these arms and is, therefore, closer to the pivot end than to the swinging end thereof. Also the point of engagement of the bent end 51 of the swinging arm 53 and bent end 52 on the arm 54 with the lug 50 on the forked arms 48 and 49 is similarly between a point in the middle of the length of these arms and the pivot end thereof so that when the slowly moving weighted arms 33 and 34 engage with and operate to actuate the arms 53, 48 or 54, 49, the movement of the disks 46 and 47 on the ends of the arms 48 and 49, owing to the compound leverage, is very quick. (The ratio shown is 15 to 1.)

Mounted upon the bosses 63 on the front side of the frame 15 of the controller 3 is the annular face 64 of the controller, which is formed of insulating material and to which is secured the series of segmental metallic contacts engaged by the spring pressed fingers 17, 18, 19, 20 and 21, 22, 23, 24 on the arm 16 of the controller. The insulating material forming the annular face 64 of the controller (see Fig. 7) is provided with a series of metallic contacts 65, 66, 67, 68, 69, 70, and 71, 72, 73, 74, 75 and 76 which are arranged in two sets, one for the upward and one for the downward movement of the skip car or bucket upon the skip hoist and are engaged by the spring pressed fingers on the swinging controller arm 16. (When a double skip is employed, the two sets of contacts will, in effect, operate each to control the upward movement of one skip car or bucket, as in such case one skip car will be lowered while the other is being lifted.)

Referring now to Fig. 7 which shows, diagrammatically, the motor, switchboard, geared controller 3, safety cut-out 4 and operator's switch 5, the numeral 77 designates the manually operated knife switch by which the positive and negative line conductors 78 and 79 leading from the power house or generator are connected to the switchboard.

55 A removable safety plug 80 is provided which is in circuit with the knife switch which connects the control circuit to the negative conductor 79 of the main circuit, and ordinarily the plug remains in position until such time as it is desired to inspect or repair the skip hoist mechanism. In such cases, the removal of the safety plug prevents possibility of the apparatus being started through the medium of the operator's switch 5 and possible injury to the per-

son or persons working on the apparatus. Provision is made for locking the plug out with a padlock.

The circuit of the hoist motor, the armature winding of which is indicated at 92, 70 comprises overload relays 81 and 82 having hinged contact members 83 and 84, respectively, which control the supply of current to the motor in a manner to be later described. The relays 81 and 82 are provided with any suitable or usual trigger mechanism (not shown) to retain them in an open position. The trigger mechanism is controlled by reset coils 85 and 86 which, when energized, operate in a well known manner 80 to permit the closing of the relays. The reset coils 85 and 86 are controlled by the operator's switch 5 and are arranged to be energized only when the switch handle is in its "off" position. 85

Reversing switches 87, 88, 89 and 90 are arranged in pairs and are mechanically connected in order that each pair may be actuated by a single magnet coil. The respective pairs of switches are mechanically interlocked by a pivoted lever 91 to insure that only one pair of switches may be closed at one time. 90

A sectional starting resister 99, which is in series relation with the motor armature winding 92, is controlled by an electromagnetic switch 103 and series lockout switches 104, 105 and 106 which operate successively to shunt sections of the resister. The magnet coil of switch 103 is controlled 100 by a series lockout relay 100.

A resister 93, which is employed for dynamic braking and is adapted to be connected in shunt relation to the motor armature by normally closed switches 94 and 95, 95 is controlled by electromagnetic switches 96 and 97. The switch 96 is controlled by a series lockout relay 98 which is adjusted to operate when the current is below a relatively low predetermined value. The switch 110 97 is controlled by the automatic controller 3 and is arranged to close almost at the end of the path of movement of the controller to render the movement of the drum very slow as it approaches the extremity of its path 115 of movement.

A magnetic switch 108 which is arranged with its operating coil to be controlled by the relay 107, operates to cut out or short-circuit the series field 101 and thus connect 120 the armature 92 directly to the negative line conductor 79 of the main circuit through the circuit breaker 102.

The operating coils of the circuit breaker 102 and of the reversing switches 87-88 or 125 89-90 which operate in pairs are connected through the contacts 83 and 84 of the overload relays 81 and 82, the contact 109 of the shunt field protective relay 113, the slack rope switches 110 and 111, and the safety 130

plug 80 to the negative line conductor 79, so that opening of any one of these will render the circuit breaker 102 and reversing switches 87-88 or 89-90 inoperative, causing them to drop out and open the main circuit, the further operation of these switches being made impossible until the control circuit through the coils thereof is again closed or completed.

- 10 The shunt field 112 of the motor is connected to the line conductors 78 and 79 of the main circuit through the coil of a shunt field protective relay 113 so that it is always energized when the main knife switch 77 is closed, as is also the coil of the shunt field protective relay 113. In case of an open circuit in the shunt field 112, the shunt field protective relay 113 will become deenergized, and its contact 15 will open the control circuit through the operating coils of the circuit breaker 102 and the reversing switches 87-88 or 89-90 and cause the circuit breaker 102 and reversing switches 87-88 or 89-90 to 20 open the main circuit.

A magnetic brake 114, which coacts with any suitable member of the apparatus is arranged to set by gravity when its magnet coil is not energized. The circuit of the 30 brake magnet coil is controlled by magnetic switches 115 and 116 so that when the switches are closed the brake is released. The operating coils of the switches 115 and 116 are in turn controlled by an auxiliary contact on the circuit breaker 102 and the upper auxiliary contacts on the reversing switches 87 or 89, so that when the circuit breaker 102 and a pair of the reversing switches 87-88 or 89-90 close, 35 the brake 114 is released, and when either of these switches opens, the switches 115 and 116 open and allow the brake 114 to set, and assist in stopping the motor.

As shown in Fig. 7, the operator's switch 45 5 has an operating lever 117 provided with two contacts 118 and 119, and has a series of stationary contacts 120 and 121 which are arranged to be connected together by the contact 118 and like contacts 122 and 50 123 arranged to be connected together by the contact 119 when the switch lever 117 is thrown into the up or hoisting position. This switch 5 is also provided with stationary contacts 124 and 125 positioned to be 55 engaged by the lever contact 118, and contacts 126 and 127 positioned to be engaged by the lever contact 119 when the switch lever 117 is thrown into the down position, or position to reverse the direction of 60 the motor and drums from the case just referred to above. In addition there are two stationary contacts 128 and 129 on the operator's switch 5, that are positioned to be connected by the contact 118 when the lever 65 117 is in the vertical position shown,

so as to cause the reset coils 85 and 86 of the overload relays 81 and 82 to be energized and reset the overload relays in the manner described above, after these relays have been tripped by a predetermined excessive value of current through the main circuit.

The automatic geared controller 3 is provided with stationary contacts 65, 66, 67, 68, 69 and 70 connected together at different positions of the movable arm 16 by the electrically connected contact fingers 17, 18, 19 and 20, (which are conveniently shown in the diagrammatic representation as a single, long, solid contact) are provided to operate the magnetic switches in proper order when the hoist is run in the other direction.

The quick-break switch 46 is connected to the contact 69 of the geared controller 3 and the quick-break switch 47 to the contact 75, these switches opening the control circuit to the magnetic switches at the end of the travel of the hoist.

The safety cut-out 4, which is connected 90 between the geared controller 3 and the switchboard, is also provided with stationary contacts 130, 131 and 132, 133, the pairs of contacts being arranged to be connected to complete the control circuit for the reversing switches 87, 88, 89 and 90 and the circuit breaker 102 by engagement of the contacts 134 and 135 on the mechanically operated arm 136 forming part of the safety cut-out 4.

The arm 136 on the safety cut-out 4 is fixed to the U-shaped bracket 137, which is counterweighted to normally move and yieldingly hold the arm 136 in its vertical position. The bracket 137 is pivotally mounted on a shaft 138 which is rotatably mounted in bearings on the side of the pedestal bearing 7. The inner end of the shaft 138 has a spur gear 139 keyed thereto meshing with and actuated by the spur pinion 140 on the stub shaft 140^a which projects from the side of the pedestal bearing 7. Also mounted on the shaft 140^a and rotated by the gear 140 is a spur gear 141 meshing with and driven by the spur gear 142 keyed on the drum shaft 6 between the end of the drum 2 and adjacent end of the shaft bearing 7. (See Figs. 1 and 9).

The shaft 138 has a screw-threaded portion 138^s, which is positioned between the parallel legs of the U-shaped bracket 137 and has a nut 143 thereon which is slidingly connected to the U-shaped bracket 137 so as to permit lengthwise movement of the nut 143 on the rotating shaft 138^a and to rock the bracket 137 when the nut 143 is turned by engagement with one or the other of the nuts 144, 145 clamped on the shaft 138.

The nuts 144 and 145, which are adjustably mounted on the screw-threaded por-

tion of the shaft 138^a, one on each side of the nut 143 are clamped in position thereon so as to rotate with the screw 138. The nuts 144 and 145 engage with the nut 143 and, 5 through the U-shaped bracket 137 connected to the nut 143, rock the nut and the bracket 137 and the arm 16 on the safety cut-out, which is connected to the bracket 137 to operate the arm 16 and move it from its 10 vertically depending position at the end of each hoisting and lowering operation of the skip. The gears 139, 140, 141 and 142 are of such size as will rotate the screw threaded portion 138^a of the shaft 138 so 15 as to move the nut 143 lengthwise on the shaft 138^a and cause it to engage with one or another of the nuts 144 and 145, depending on the direction of movement of the skip, to operate the arm 16 of the safety- 20 cut-out 4. The distance between the nuts 144 and 145 is adjusted by unclamping and moving these nuts on the shaft 138^a for the required amount, which differs with 25 variations in the height of the skip hoist or, what is the same thing, the length of travel of the skip car.

The operation of a skip hoist equipped with my improved operating and controlling mechanism will now be described: It 30 is assumed that in starting the apparatus in operation the skip car or bucket of the hoist is positioned at the bottom of the skip track. (With a double skip, one skip car will always be located at the bottom when 35 the other is at the top of the skip hoist track.) The switches all being thrown into open position, except mechanically closed switches 94 and 95, and overload relays 83 and 84 and the swinging arm or lever 117 40 of the operator's switch 5 being positioned in the vertical or off position as at C in Fig. 7, the swinging arm 16 of the automatic, mechanically actuated, geared controller 3 is held in position A by engagement of the 45 lug 27 on the wheel 25 with the lug 28 on the spur gear 12, and the arm 34 is held in the raised position shown in Fig. 6 by engagement of the lug 30 on the wheel 25 with the lug 32 of the weighted arm 34, and the 50 mechanism connecting the rope drum shaft 6 with the safety cut-out 4 is adjusted until the swinging arm 136 of the cut-out is in position at B, Fig. 7. The safety plug 80 is then inserted in place and the main 55 switch 77 is closed. The shunt field winding 112 is energized by a circuit extending from the positive side of switch 77 through the coil of overload relay 81, conductor 146, coil of relay 113 and shunt field winding 60 112 to the negative side of the line. The coil of relay 113 is thus energized to cause switch member 109 to bridge its coacting contact members. The reset coils 85 and 65 86 of the overload relays 81 and 82 are energized by a circuit extending from the

positive side of the switch 77 through conductor 147, contact members 124, 128, 118 and 129 of operator's switch 5, conductor 148 and coils 85 and 86 in parallel to the negative side of the line. The lever 117 of 70 the operator's switch 5 is then actuated to the "up" position indicated by C' to connect contact members 120 and 122 to contact members 121 and 123. The control circuits comprising these contact members are 75 thus completed through the controller 3 and the safety cut-out 4. A circuit is completed which extends from the positive side of switch 77 through the conductor 147, contact members 124, 120, 118 and 121 of 80 switch 5, contact member 67 of controller 3, contact members 132, 135 and 133 of cut-out 4, conductor 150, auxiliary contact member 151, coil of reversing switches 87 and 88, conductor 152, coil of switch 102, contact members 84 and 83, switch member 109, slack rope switches 110 and 111, conductor 149 and safety plug 80 to the negative side of the line. The switch 102 and 85 reversing switches 87 and 88 are closed by 90 the energization of the circuit just described. Current then traverses a circuit extending from the positive conductor 78 through the switch 77, the coils of relays 81 and 98, reversing switch 87, armature winding 92, reversing switch 88, relay 100, resistor 99, series field winding 101, switch 102 and overload relay 82 to the negative side of the line. Simultaneously with the closing of the switches 87 and 88, an auxiliary contact member 153 on the switch 87 95 closes a circuit for the coils of switches 115 and 116 which extends from the switch 87, which is connected to the positive side of the line as above described, through contact member 153, conductor 154, coils of switches 115 and 116 in parallel, conductor 155, auxiliary contact member 156 of switch 102, contact members 84 and 83, switch member 109, switches 110 and 111, conductor 149 and safety plug 80 to the negative terminal. The switches 115 and 116 then close to complete the circuit of the coil of the electromagnetic brake 114 which is thereupon released to permit the rotation 100 of the motor shaft. A circuit is also completed from the positive terminal of switch 77 through conductor 147, contact members 124, 120, 118 and 121 of switch 5, contact 105 members 67, 17 and 68 of controller 3, contact members 123, 119, 122 and 126 of switch 5, conductor 157, coil of dynamic braking switch 94, conductor 158, contact member 156, switch members 84 and 83, switch member 109, switches 110 and 111, conductor 149 110 and safety plug 80 to the negative terminal of switch 77. The coil of dynamic braking switch 95 is also connected to the positive side of the line through the auxiliary contact member 159, which is now in its position 115 120 125 130 135 140 145 150 155 160 tion corresponding to the closed position of switch 88. The dynamic braking switches are accordingly opened to remove a shunt circuit for the motor armature which includes the dynamic braking resistor 93. The motor then starts and is accelerated automatically by the successive operation of relay 100 and switches 103, 104, 105 and 106. When the current through the coil of lock-out relay 100 falls below a predetermined value, the relay closes to complete the circuit of the coil of switch 103 which extends from the positive terminal of switch 77 through conductor 147, contact members 124, 120, 118 and 121 of switch 5, contact members 67, 17 and 68 of controller 3, contact members 123, 119, 122 and 126 of switch 5, conductor 157, auxiliary contact members 160 and 161 of switches 94 and 95, coil of switch 108, relay 100 and safety plug 80 to the negative terminal of switch 77. The switch 103 then closes to shunt a section of the resistor 99. The closing of switch 103 completes the circuit of the coil of series lockout switch 104 and the latter operates to short circuit a second section of the resistor 99 when the current falls below a predetermined value. The switches 105 and 106 operate in a similar manner to complete a short circuit for the resistor. The switch 106 closes the circuit of the coil of relay 107 which, in turn, operates to close the circuit of the magnet coil of switch 108. The latter then short circuits the series field winding 101.

After the motor is started, its continued movement causes the rope drum 2 to rotate so as to wind the hoist rope upon the drum 2, and the movement of the drum shaft 6 transmitted through the gears and connecting mechanism to the arm 16 of the geared controller 3, permits the arm 16 to be moved by the weighted arm 34 which is engaged with the wheel 25, until the arm 16 is in its horizontal position as at A¹. (Fig. 7.) This arm 16 is then held in such position by the weighted arms 33 and 34, until by continued operation of the drums the weighted arm 33 is engaged and moved by the lug 29 on the slowly rotating wheel 25, which is actuated by rotation of the rope drums and drum shaft 6 in the shaft bearings 7. At the same time that the arm 16 of the geared controller 3 begins to move from its position A, the connecting gearing releases and permits the swinging arm 136 on the safety cut-out 4 to fall or swing by gravity, until in the operative position B¹, in which position the arm 136 remains until just after the arm 16 of the geared controller 3 has passed its position A³. (Fig. 7.)

When the skip car reaches a predetermined point in a blast furnace hoist, usually about 15 feet from the limit of travel, the

lug 26 on the wheel 25 is engaged by the lug 28 on the gear 12, which causes the shaft 13 to recontinue its rotative movement and carry with it the arm 16 of the controller 3, the lug 29 of the wheel 25 engaging with lug 31 on the arm 33 and causing the arm 33 also to rotate on the shaft 13, and when the arm 16 reaches the position A², the control circuit through the coils of the mechanically closed switches 94 and 95 is opened, allowing these switches to close and placing the shunt through the resistance 93 around the armature 92. At the same time the closing motion of the switches 94 and 95, through their auxiliary contacts 160 and 161, opens the control circuit through the coils of the switches 103 and 108, which drop open and cause all of the starting resistance 99 and the series field 101 to be again inserted in series with the armature 92. As the motor and drums continue to rotate, but at a very much slower rate, the armature shunt through resistance 93 is automatically decreased in two steps, one under the control of the shunt switch 96 which is actuated by the lock-out relay 98, and the second step by the switch 97 which is actuated through the contact 70 of the geared controller 3 when the arm 16 reaches its position A⁴, this movement reducing the rotation of the motor to a very slow or creeping speed, which continues until, when the arm 16 reaches its position A⁵, the quick-break switch 46 is opened by engagement of the cap-bolt 58 on the arm 100 33 with the lug 56 as has been described, opening the control circuit through the operating coils of the reversing switches 87, 88 and the circuit breaker 102, so as to disconnect the motor from the line, and open 105 the control circuit through the coils of the switches 115 and 116, so as to permit the shunt brake 114 to set.

The brake 114 is assisted in stopping the motor by dynamic braking on the shunt field 112, which effect is obtained as long as the motor is rotating by reason of the fact that the mechanically closed switches 94 and 95 maintain the shunt around the armature 92.

The arm 136 of the safety cut-out 4 must be set to operate just after the controller arm 16 has passed the position A³. Should, for any reason, the controller 3 be inoperative, the safety cut-out 4 will open the control circuit through the operating coils of the reversing switches 87, 88 and the circuit breaker 102, and cause these switches and the circuit breaker to open and disconnect the motor from the line, set the shunt brake, 125 and to set and at the same time deenergize the coils of the mechanically closed switches 94 and 95 so as to release and close these switches, which movement places the shunt around the armature 92 to give dynamic 130

braking on the shunt field 112 and assist the brake 114 in stopping the motor. When the controller 3 operates properly, the safety cut-out 4 is rendered inoperative by the completion of the control circuit through the coils of the switches 87, 88 and 102 by the contact 69 on the controller 3, while the arm 16 is traveling from its position A³ to position A⁵.

10 In operating the hoist to lower the lifted skip car, the operator simply reverses the operator's switch 5 and the above described cycle is repeated, the only difference being that the opposite end of the controller arm 16 and the opposite side of the controller 3 and safety-cut-out 4 become effective.

15 The motor may be stopped at any point in the travel by bringing the lever 117 of the operator's switch 5 into position C, (or the off position) this position of the arm disconnecting the motor from the line and permitting the mechanically closed switches 96 and 97 to close, and causing dynamic braking on the shunt field 112 which assists the 20 shunt brake. The motor may be again started in either direction by moving the lever 117 of operator's switch 5 to the proper position.

25 In the event of an overload, or should a ground occur on either side of the line, the overload relays 81 and 82 will open the circuit breaker 102 and the reversing switches 87, 88, and the shunt brake 114 will set, dynamic braking on the shunt field being 30 obtained in the same manner as has just been described. Movement of the operator's switch lever 117 to the off position at C will then cause resetting of the overload relays.

35 Should the shunt field circuit open, the shunt field relay 113 will open the control circuit through its contact 109 causing the circuit breaker 102 and the reversing switches 87, 88 to open the main circuit and the shunt brake 114 will set. The shunt field 40 is maintained continuously as long as the knife switch 77 is closed so as to insure at all times dynamic braking of the motor. As the circuit breaker 102 is opened simultaneously with the reversing switches 87, 88 or 45 89, 90, additional safety is afforded in case one of the switches should stick and fail to open.

50 The advantages of my invention will be apparent to those skilled in the art. By means of my improved mechanically operated controller and mechanically operated safety cut-out the hoist operations are performed without the necessity of regulation of the hoisting speed by the operator. The electric connections to the controller and cut-out and the mechanical connection between the controller and cut-out with the hoisting drum cause the motor to start slowly and travel at a gradually accelerating speed through the desired part of the 55

travel of the skip car, to travel at a maximum speed for the desired part of the travel, and to gradually slow down and to come to a stop at the desired point.

55 The arrangement of magnetic and mechanically closed switches and relays shown prevents the possibility of damage by reason of failure of current supply or of breakage to the hoist operating mechanism.

60 Modifications in the construction and arrangement of the parts may be made without departing from my invention.

I claim:

1. In a hoist operating and controlling system, a controller electrically connected to regulate and control the operation of the hoist motor and comprising a swinging contact arm, a shaft for turning the arm, a shaft operating member and means actuated by the hoist driving mechanism for intermittently turning said member. 80

2. In a hoist operating and controlling system, a controller electrically connected to regulate and control the operation of the hoist motor and comprising a swinging contact arm, a shaft for turning the arm, a shaft operating member, means actuated by the hoist driving mechanism for intermittently turning said member and adjustable means connecting the member turning 90 means and said member whereby angular turning movement of the member turning means relative to that of the member is varied. 95

3. In a hoist operating and controlling system, a controller electrically connected to regulate and control the operation of the hoist motor and comprising a swinging contact arm, a shaft for turning the arm, a shaft operating member, means actuated by the hoist driving mechanism for intermittently turning the said member, and a swinging arm arranged to engage the said member and thereby hold the contact arm stationary during portions of the movement 105 of the member turning means. 110

4. In a hoist operating and controlling system, a controller electrically connected to regulate and control the operation of the hoist motor and comprising a swinging contact arm, a shaft for turning the arm, a shaft operating member, means actuated by the hoist driving mechanism for intermittently turning said member, a swinging weighted arm arranged to engage said member and thereby hold the contact arm stationary during portions of the movement of the member turning means and a stop to limit the movement of the swinging arm in 115 one direction. 125

5. In a hoist operating and controlling system, a controller electrically connected to regulate and control the operation of the hoist motor and comprising a swinging contact arm, a shaft for turning the arm, a 130

- shaft operating member, means actuated by the hoist driving mechanism for intermittently turning said member, and a plurality of swinging arms arranged to engage said member and thereby hold the contact arm stationary during portions of the movement of the member turning means.
6. In a hoist operating and controlling system, a controller electrically connected to regulate and control the operation of the hoist motor and comprising a swinging contact arm, a shaft for turning the arm, a shaft operating member, means actuated by the hoist driving mechanism for intermittently turning said member, a plurality of swinging weighted arms arranged to engage said member and thereby hold the contact arm stationary during portions of the movement of the member turning means, and a stop to limit the movement of the swinging arms in one direction.
7. In a hoist operating and controlling system, a controller electrically connected to regulate and control the operation of the hoist motor and comprising a swinging contact arm, a shaft for turning the arm, a shaft operating member, means actuated by the hoist driving mechanism for intermittently turning said member, a swinging arm arranged to engage said member and thereby hold the contact arm stationary during portions of the movement of the member turning means, and adjustable means connecting the arm and said member whereby the relative angular movement of said arm and said member is varied.
8. In a hoist operating and controlling system, a controller electrically connected to regulate and control the operation of the hoist motor and comprising a swinging contact arm, a shaft for turning the arm, a shaft operating member, means actuated by the hoist driving mechanism for intermittently turning said member, a plurality of swinging weighted arms arranged to engage said member and thereby hold the contact arm stationary during portions of the movement of said member turning means, and adjustable means connecting the weighted arms and said member whereby relative angular movement of the arms and said member is varied.
9. In a hoist operating and controlling system, a controller electrically connected to regulate and control the operation of the hoist motor and comprising a swinging contact arm, a controller having a plurality of contacts engaged by the contacts on the contact arm, a shaft for turning the contact arm, a shaft operating member, a spur gear having means engaging with and intermittently rotating said member, said gear being operatively connected to and actuated by the hoist driving motor, a weighted arm pivoted on the arm shaft and arranged to be lifted by said member, and a quick break switch electrically connected to the motor control circuit and arranged to be opened by said swinging arm in predetermined positions of said arm.
10. In a hoist operating and controlling system, a controller electrically connected to regulate and control the operation of the hoist motor and comprising a swinging contact arm, a controller having a plurality of contacts engaged by the contacts on the contact arm, a shaft for turning the contact arm, a shaft operating member, a spur gear having means engaging with and intermittently rotating said member, said gear being operatively connected to and actuated by the hoist driving motor, a swinging arm pivoted on the arm shaft and arranged to be lifted by said member, a quick break switch, a compound lever for opening said switch, and means on the counterweight arm to engage said levers and open said switch.
11. In a hoist operating and controlling system, a controller electrically connected to regulate and control the operation of the hoist motor and comprising a swinging contact arm, a controller having a plurality of contacts engaged by the contacts on the contact arm, a shaft for turning the contact arm, a shaft operating member, a spur gear having means engaging with and intermittently rotating said member, said gear being operatively connected to and actuated by the hoist driving motor, a swinging arm pivoted on the arm shaft and arranged to be lifted by said member, a quick break switch, a compound lever for opening said switch, and means on the arm to engage said levers and open said switch, said means being adjustable to regulate the time interval between opening movements of said compound levers.
12. In a hoist operating and controlling system, a controller electrically connected to regulate and control the operation of the hoist motor and comprising a shaft having a controller arm fixed thereon, contacts on said arm engaging the series of segmental contacts on the controller face, a wheel mounted on and turning with the shaft, a spur gear rotatable on the arm shaft having means intermittently engaging with and turning the wheel and shaft, means for turning said spur gear, and a swinging arm pivoted on the shaft and arranged to be lifted by said wheel, and to hold the controller arm stationary during portions of the wheel turning movements.
13. In a hoist operating and controlling system, a controller electrically connected to regulate and control the operation of the hoist motor and comprising a shaft having a controller arm fixed thereon, contacts on said arm engaging the series of segmental contacts on the controller face, a wheel mounted on and turning with the shaft, a

spur gear rotatable on the arm shaft having means intermittently engaging with and turning the wheel and shaft, means for turning said spur gear, and a pair of oppositely extending swinging counterweight arms pivoted on the controller arm shaft and arranged to be lifted by said quadrant, and co-acting to hold the controller arm stationary during portions of the wheel turning movement.

14. In a hoist operating and controlling system, a controller electrically connected to regulate and control the operation of the hoist motor and comprising a shaft having a controller arm fixed thereon, contacts on said arm engaging the series of segmental contacts on the controller face, a wheel mounted on and turning with the shaft, a spur gear rotatable on the arm shaft having means intermittently engaging with and turning the wheel and shaft, means for turning said spur gear, and a pair of oppositely extending swinging arms pivoted on the controller arm shaft and arranged to alternately engage with and be lifted by said wheel and co-acting to hold the controller arm stationary during portions of the wheel turning movement.

15. In a hoist operating and controlling system, a controller electrically connected to regulate and control the operation of the hoist motor and comprising a shaft having a controller arm fixed thereon, contacts on said arm engaging the series of segmental contacts on the controller face, a wheel mounted on and turning with the shaft, a spur gear rotatable on the arm shaft having means intermittently engaging with and turning the wheel and shaft, means for turning said spur gear, a swinging arm pivoted on the shaft and arranged to be lifted by said wheel, and to hold the controller arm stationary during portions of the wheel turning movements, and adjusting means between the arm and wheel whereby the lifting movement of the arm by the quadrant is varied.

16. In a hoist operating and controlling system, a controller electrically connected to regulate and control the operation of the hoist motor and comprising a shaft having a controller arm fixed thereon, contacts on

said arm engaging the series of segmental contacts on the controller face, a wheel mounted on and turning with the shaft, a spur gear rotatable on the arm shaft having means intermittently engaging with and turning the wheel and shaft, means for turning said spur gear, and adjusting means between the spur gear and wheel whereby the turning movement of the wheel by the spur gear is varied.

17. In a hoist operating and controlling mechanism, a controller comprising a shaft having a controller arm mounted thereon, a wheel secured on said shaft to rotate therewith, a gear wheel having means engaging with and rotating said wheel, swinging weighted arms loosely mounted on said shaft arranged to engage with and move the wheel and shaft to swing and hold the controller arm, and quick-break switches on said controller, said switches comprising a pair of pins and swinging lever pivoted on the controller and having a disk thereon engaging with and connecting said pins, said swinging lever being arranged to engage with and be moved to disengage the disk and pins and open the switch by contact with the engaging swinging arm.

18. In a hoist operating and controlling mechanism, an electric controller comprising a face having segmental contacts thereon, a swinging arm having contact fingers operatively engaging the segmental contacts, a shaft on which said arm is mounted to rotate therewith, a gear wheel rotatably mounted on the shaft, a wheel secured on and rotating said shaft having means engaging with and turning said shaft and controller arm thereon, said gear wheel and said wheel having coacting means whereby the wheel is moved by the gear wheel, and oppositely extending counterweighted arms engaging with and yieldingly holding said wheel and arm against movement while said gear wheel is moving through part of its rotary movement.

In testimony whereof I have hereunto set my hand.

EUGENE FRIEDLAENDER.
